UNITED STATES PATENT OFFICE

148,791

DESIGN FOR AN ALPHABET

Nelson Kalnitz, Buffalo, N. Y.

Application August 3, 1946, Serial No. 132,279

Term of patent 14 years

(Cl. D64—12)

To all whom it may concern:

Be it known that I, Nelson Kalnitz, a citizen of the United States, residing at Buffalo, in the county of Erie and State of New York, have invented a new, original, and ornamental Design for an Alphabet, of which the following is a specification, reference being made to the accompanying drawing, forming a part thereof.

Fig. 1 is a face view of the letters of an alphabet, showing my new design; and Fig. 2 is a perspective view of the letter A.

I claim:

The ornamental design for an alphabet, substantially as shown.

NELSON KALNITZ.
